UNITED STATES PATENT OFFICE

2,532,529

FLUID-BLAST ELECTRIC CIRCUIT BREAKER

Donald Foster Amer, Newcastle-on-Tyne, England, assignor to A. Reyrolle & Company Limited, Hebburn-on-Tyne, England, a British company

Application January 20, 1948, Serial No. 3,243
In Great Britain February 3, 1947

14 Claims. (Cl. 200—148)

1 This invention relates to fluid-blast electric circuit-breakers of the kind in which relative movement of the co-operating contacts is effected by fluid pressure within an arcing chamber or contact enclosure.

In an electric circuit-breaker according to the invention one or each of the co-operating contacts is located by a flexible or resilient device (such for example as a diaphragm, bush or bellows), situated within the arcing chamber or enclosure so that frictional sliding or guide surfaces for the contact or contacts can be obviated.

The contacts may separate adjacent to at least one nozzle or vent through which the arc is driven by the blast of arc-extinguishing fluid from the enclosure. For example, one or each of the co-operating contacts may itself constitute a nozzle or vent. In one arrangement, the co-operating contacts carry the relatively movable parts of a fluid-tight valve which controls the flow of arc-quenching fluid from the enclosure to an exhaust conduit or conduits formed, for example, in one or each of the co-operating contacts.

In the accompanying drawings,

Figures 1 to 3 are diagrammatic representations, in vertical section, of three arrangements of single-break circuit-breaker embodying the invention,

Figure 4 shows, also in vertical section, one unit of a high voltage multi-break circuit-breaker having a plurality of circuit-breaker units arranged in a series stack.

Figure 5 is a diagrammatic representation of such multi-break circuit-breaker with contact control by pressure release.

Figure 6 similarly illustrates a modification of Figure 5 in which each pair of co-operating contacts together form a fluid-tight seal, and

Figure 7 is a modification of Figure 6, the contact control being effected by control of the supply of pressure fluid.

In the construction shown in Figure 1, the single-break circuit-breaker comprises a fixed arcing contact A disposed coaxially within an externally shedded cylindrical insulating enclosure B, the lower end of the fixed contact A being electrically connected to a spider A¹ carried by the enclosure B and constituting one pole X of the circuit-breaker. Mounted on the upper end of the enclosure B is a metallic nozzle member or cap C which incorporates a nozzle C¹ whose axis is substantially in alignment with the axis of the fixed contact A, the nozzle C¹ flaring towards an auxiliary electrode D electrically connected to the nozzle member C. Disposed laterally with respect to the fixed contact A and adjacent to the

nozzle C¹ is a moving contact E carried by a flexible diaphragm, disc or bellows (diagrammatically indicated at E¹) of conducting material arranged in a lateral recess C² on the nozzle member C.

5 The moving contact E is resiliently urged into contact with the associated fixed contact A by the inherent resilience of the diaphragm E¹ supplemented by a biasing spring E².

When the circuit-breaker is to be opened, an **10** inlet control valve F¹ at the base of the enclosure B is opened so that pressure fluid, for example air under pressure, is supplied from a receiver or reservoir F to the interior of the enclosure B. The fluid pressure within the enclosure B now

15 acts on the diaphragm E¹ and thus causes the moving contact E to be retracted from the fixed contact A. The arc initiated between the fixed and moving contacts A, E is now transferred, by the blast of deionising fluid, from the moving contact E to the nozzle member C and, through the nozzle C¹, to the auxiliary arcing contact D, the arc being thus extinguished. As soon as the inlet control valve F¹ is closed, the moving contact E will be automatically restored to its closed position.

20 In the latter respect the valve F¹ and a series break isolating switch indicated at Z are sequentially controlled so that when the arc has been extinguished the isolating switch Z is opened before the valve F¹ is reclosed, re-establishment of the circuit being subsequently effected by closing the isolating switch Z.

It will be apparent that, since the moving contact E is located solely by the resilient diaphragm E¹, frictional sliding surfaces or guide surfaces for

35 the moving contact E are wholly obviated. Though, with this construction, it is preferred to employ a locating device E¹ of metal since this provides also for positive electrical connection between the moving contact E and the nozzle member C and, moreover, will satisfactorily withstand the effects of arcing, it may be desirable in some instances to employ a resilient or flexible locating device of insulating material, such for example as rubber. To this end, the moving contact

40 E may be located by a rubber bush, disc or sleeve, the moving contact being electrically connected to the nozzle member C through one or more flexible leads. Whether the locating device E¹ is of conducting material or of insulating material, however, it will be understood that the flow of deionising fluid through the enclosure B to the nozzle C¹ will tend to sweep the products of arcing away from the flexible locating device E¹ thus tending to protect this device against the effects of arcing.

In the construction shown in Figure 2 the in-

insulating enclosure G is furnished with a contact ring or spider G¹ which constitutes one pole X of the circuit-breaker, the spider G¹ carrying a fixed contact G² disposed coaxially within the enclosure G. Arranged in alignment with the fixed contact G² and secured to a second fixed spider H¹ carried by the enclosure G (this spider H¹ constituting the second pole Y of the circuit-breaker) is a hollow or tubular carrier H for a moving contact ring H² which is located on the tubular carrier by a flexible disc H³ of conducting material, or of insulating material such, for example, as rubber bonded to the contact H² and carrier H. A biasing spring H⁴ disposed within the hollow contact carrier H urges the moving contact H² into abutment with the fixed contact G². If the flexible locating device is of conducting material this device itself forms the necessary electrical connection with the tubular or hollow contact carrier H and therefore with the second pole Y of the circuit-breaker, but if the flexible locating device H³ is of insulating material, the necessary electrical contact may be provided by one or more flexible leads H⁵ arranged within the hollow contact carrier H.

The spider H¹ is provided with an exhaust passage H⁶ so that, assuming the contacts G²H² to be in mutual abutment and it is desired to open the circuit-breaker, the inlet control valve F¹ is opened so that fluid is delivered from the reservoir F to the enclosure G. The pressure of the fluid in the enclosure G then acts on the flexible or resilient locating device H³ so as to separate the contacts G²H² against the action of the biasing spring H⁴. A blast of fluid then flows from the enclosure G between the contacts G²H² and thence out through the exhaust passage H⁶ to the atmosphere. The moving contact H² may be in the form of a nozzle so that the arc initiated between the contacts G²H² when they separate is transferred through the nozzle and is thus extinguished.

It will be appreciated that either the fixed contact or the moving contact, or both, may be hollow and nozzle-like, though it will usually be preferred to make the fixed contact in the form of a nozzle, for example as will be described below with reference to Figures 3 and 4. In some instances it may be preferred to provide two contact tips or plates each carried by a resilient or flexible locating disc, diaphragm, bush or bellows, either or each of the two carriers for the two contacts (both of which are thus movable) being hollow and furnished with exhaust passages.

According to the construction shown in Figure 3, instead of the separation of the contacts being controlled by an inlet control valve, that is to say by a valve controlling the delivery of pressure fluid to the enclosure, the separation of the contacts is effected by an outlet control valve which relieves or releases the fluid pressure acting on the movable contact externally to the enclosure. In this construction each of the two spiders J, K is hollow, so as to provide for the exhaust or release of pressure fluid therefrom. To this end, one spider J carries a hollow fixed contact J¹ having its open end J² within the enclosure J³ formed as a nozzle. The second spider K carries a hollow fixed tube K¹ in axial alignment with the hollow contact J¹. Co-operating with the nozzle-like end J² of the fixed hollow contact J¹ is a movable contact K² located on the carrier K¹ by a flexible or resilient

locating device K³ in the form of a disc, bush or bellows. As with the constructions above described, the movable contact K² may either be electrically connected to its hollow carrier K¹ by the locating device K³ if this is of conducting material or, if the device K³ is of insulating material (for example a rubber disc), the movable contact K² may be connected to the spider K through one or more flexible leads K⁴ disposed within the tubular carrier K¹ which also houses a biasing spring K⁵ for restoring the moving contact K² to its closed position after opening of the contacts.

The hollow carrier K¹ has a relief passage K⁶ communicating with a relief conduit provided with an outlet control valve K⁷ so that, when the fluid pressure is maintained within the enclosure J³ from a supply conduit J⁴, opening of the outlet control valve K⁷ will result in the predominating fluid pressure within the enclosure J³ acting to separate the contacts J²K². As the two contacts separate, a blast of deionising fluid flows over the separating contacts and thence through the carrier J¹ to the atmosphere. The arc is thus blown through the nozzle-like end J² of the fixed contact, the products of arcing being discharged through the exhaust passage J⁶. The carrier K¹ is in open communication with the enclosure J³ through a bleed passage J⁸ so that, after opening the circuit-breaker and reclosing the outlet control valve K⁷, pressure fluid will leak through the bleed passage J⁸ until the pressure in the hollow carrier K¹ is again equal to that within the enclosure J³ in readiness for the next opening operation.

The invention is particularly, though not exclusively, applicable to circuit-breakers of the multi-break type comprising a plurality of contact units arranged in an aligned series or stack. In one such construction, as shown in Figure 4, each contact unit is arranged in a cylindrical sheathed enclosure B¹ furnished with an external flange-like metal annulus B² having an exhaust port or ports B⁴ through which the arc quenching fluid is discharged through an exhaust valve B³ of the flap type. The annulus B², which constitutes one terminal of the unit, forms part of a conducting spider A³ having a cylindrical carrier A² disposed coaxially within the enclosure B¹. The upper or open end A⁴ of the hollow carrier A² is formed into a nozzle-like contact, and an auxiliary arcing electrode D¹, which is also hollow, is arranged within the fixed contact A² in alignment with, but spaced below, the contact A⁴. A disc-like moving contact D² is secured to the lower end of the hollow carrier A² by means of a flexible locating device D³, such for example as a disc of copper, the moving contact D² having an axial anchorage stud D⁴ connected through adjusting nuts D⁵ and an anchorage chain D⁶ to the interior of the auxiliary arcing electrode D¹. A biasing spring D⁷ bears at its lower end against the assembly of the moving contact D² and at its upper end against an internal flange or shoulder D⁸ of the auxiliary arcing electrode D¹, the travel of the moving contact D² under the action of the biasing spring D⁷ being thus limited by the effective length of the anchorage chain D⁶ as determined by the adjusting nuts D⁵.

Thus, the fixed contact A², A⁴, auxiliary electrode D¹ therein, the movable contact D² immediately below the fixed contact, and the terminal annulus B² with whose exhaust port or ports B⁴

the interior of the carrier A^2 is in open communication, together constitute one contact unit associated with one enclosure B^1 , and it is to be understood that this unit, all parts of which are at the same potential, does not in itself constitute a break. When, however, a plurality of the units are secured together in a series stack by means of clamps B^5 associated with the terminal annuli B^2 at the lower ends of the units and terminal annuli B^6 at their upper ends, the moving contact D^2 of any one unit will bear against the rim of the nozzle A^4 at the upper or open end of the next lower unit, the current flowing from one pole of the circuit-breaker constituted by the lowermost terminal annulus B^2 , through the fixed and moving contacts A^4D^2 of the stack in series and finally to the other pole of the circuit-breaker constituted by the uppermost annulus B^6 .

The interiors of the several enclosures B^1 are all in open communication with each other through openings in the spiders A^3 so that when it is desired to open the circuit-breaker an inlet control valve F^1 (as described with reference to Figure 1) is opened so that fluid under pressure is delivered from a reservoir to the enclosures B^1 . The fluid pressure within these enclosures now acts on the several moving contacts D^2 and raises them from the associated fixed contacts or nozzles A^4 . As each pair of co-operating contacts D^2 , A^4 separates, a blast of deionising fluid flows radially inwards between these contacts and through the hollow fixed contacts A^4A^2 to the atmosphere through the exhaust ports B^4 . The blast of deionizing fluid transfers the arcs initiated between the separating contacts through the nozzles A^4 to the associated auxiliary arcing electrodes D^1 , the fluid blasts finally extinguishing the arcs whereupon the closing of the inlet control valve F^1 and resulting fall in pressure within the several enclosures B^1 permits the moving contacts D^2 to be restored into abutment with their associated fixed contacts A^4 by the springs D^7 .

As in the constructions above described, the resilient locating device D^3 for the moving contact D^2 of each unit obviates the necessity for any frictional sliding or guide surfaces for any of the contacts. It will, however, be understood that though a metal disc or diaphragm has been more specifically described, the flexible or resilient locating device D^3 may be constituted by a diaphragm of insulating material such, for example, as rubber, or by a rubber sleeve or bush, or by a bellows. When the locating device D^3 is of insulating material the electrical continuity between the contact A^2 and the moving contact D^2 of each contact unit may be provided by one or more flexible leads D^8 arranged within the hollow auxiliary arcing electrode D^1 .

The shedded insulating enclosure B^1 for each contact unit is so formed that the external surface resistance path of each shed B^7 exceeds that of the cylindrical parts B^8 of the enclosure so that the greater part of the said surface resistance is at right angles to the longitudinal axis of the enclosure, or stack of aligned enclosures. A resistance or capacitance may be connected across each break of the multi-break series stack so that the voltage is substantially uniformly distributed over all the breaks. The resistances are constituted by an external semi-conducting glass on the shedded enclosures B^1 so that the resistance between any two corresponding points on any two sheds B^7 respectively is the same as or proportional to that between such corresponding points on any other two sheds B^7 .

The resistance glaze, combined with mainly radial insulation, permits the use of metal parts of adequate dimensions without increasing the length of the stack of contact units, the radial formation of the insulator sheds B^7 providing adequate surface length between the metal fittings (i. e. the terminal annuli B^2 , B^6) for the voltage distribution to be controlled by the resistance glaze. As a result, the edges of the sheds B^7 are at a potential approximately midway between those of the associated metal fittings and the overall length necessary is no more than the sum of the overall lengths of the units since the said overall length of the stack is determined by the distance between the ends of the sheds B^7 and not by the distance between the metal fittings B^2 , B^6 .

In the construction shown in Figure 5, instead of the separation of the contacts being effected by supplying fluid pressure, such for example as air, through an inlet control valve to the stacked enclosures, the said separation is effected by means of an outlet control valve F^3 which relieves or releases the fluid pressure on each movable contact L externally to the enclosure M . In this construction, each contact unit comprises a hollow fixed contact M^1 electrically connected to the moving contact L below it as described with reference to Figure 4 above. An associated hollow or tubular auxiliary arcing electrode M^2 is arranged within the nozzle-like fixed contact M^1 , the exhaust passage M^3 for each fixed contact M^1 being formed in the associated supporting spider M^4 and terminal annulus. Each tubular auxiliary arcing electrode M^2 containing the necessary biasing spring or springs M^5 for the moving contact L and the lead M^6 provided when the flexible locating device L^1 is of insulating material, is in open communication with a common relief conduit F^4 controlled by the said outlet control valve F^3 .

With this arrangement, the interiors of the aligned enclosures M , which are again all in open communication with each other through openings in the spiders M^4 , are maintained filled with the pressure fluid from the reservoir F , each tubular auxiliary arcing electrode M^2 being in open communication with the interior of the enclosure through a bleed passage such as the passage J^6 shown in Figure 3. Thus, when the contacts L , M^1 are in the abutting position shown in Figure 5, the pressure within the relief conduit F^4 is equal to that within the stacked enclosures M . When, however, it is desired to open the circuit-breaker, the outlet control valve F^3 is opened and the fluid pressure within the tubular auxiliary electrodes M^2 thus relieved. The predominating fluid pressure within the enclosures M is now effective to separate the contacts L , M^1 , so that the blasts of deionising fluid flow between the separating contacts and out through the exhaust conduits M^3 .

As indicated above, since the main contacts of the circuit-breaker automatically reclose after arc extinction, means will be provided for isolating the circuit after the arc extinction is complete. To this end, the circuit-breakers of Figures 2 to 5 will be provided with series-break isolating switches such as the switch Z described with reference to Figure 1, the isolating switch and fluid control valve being actuated sequentially, for example as shown diagrammatically in Figure 5 in which the valve F^3 is actuated by a rod P^6 which acts through a lost-motion coupling P^7 on the isolator Z .

The relatively movable contacts may have associated seatings which co-operate in a fluid-tight manner so as to constitute the relatively movable parts of a fluid-control valve. For example, as shown in Figure 6 which is a modification of the arrangement shown in Figure 5, the stack of enclosures M is again mounted upon a reservoir O with the control valve F³ and relief passage F⁴. Each moving contact L is carried by a resilient, e. g. rubber, diaphragm L¹, but in addition to the contacts L making butt contact with the fixed nozzle-like contacts M¹, each diaphragm L¹ co-operates as a resilient fluid-tight seating with a seating flange M⁷ on the associated fixed contact M¹. Thus, while the valve F³ is in the closed position the interiors of all the enclosures M are at the same pressure as that within the reservoir O which pressure also obtains within the passage F⁴ by reason of the bleed passages M⁸. By reason of the co-operating fluid-tight seating surfaces, pressure fluid cannot leak past the contacts. When the valve F³ is opened the pressure behind the diaphragm L¹ is relieved so that the predominating pressure within the enclosures M lifts the diaphragms L¹ away from the seating flanges M⁷ and a blast of deionising fluid flows inwards first over the seatings L¹, M⁷ and then through the nozzles of the fixed contacts M¹ to the exhaust passages M⁹.

In Figure 7, the stack of insulating enclosures N is mounted on a hollow shedded post insulator P having an internal blast pipe P¹ leading upwards from a reservoir F⁵ in a base F⁶ upon which the post insulator P is mounted. The blast pipe P¹ is provided with an inlet control valve P² operated by a control piston P³, itself controlled by a trip valve P⁵, in the base F⁶. An air break isolating switch Q, whose actuating spindle Q¹ lies within a control chamber N¹ interposed between the stack of enclosures N and the top of the post insulator P, is operated through a spiral gear P⁶ by a piston P⁷ controlled, for opening the switch Q, by the piston P³ and, for closing of the said switch, by a closing valve P⁸. As described with reference to Figure 6, each moving contact R¹ is carried by a resilient rubber diaphragm R which forms a fluid-tight seating in co-operation with a flange S¹ on a fixed hollow contact S.

When the circuit-breaker is in the closed condition, the inlet control valve P² in the blast pipe P¹ is closed and the series break isolating switch Q is also in the closed position. If now, the circuit-breaker is to be opened, the trip valve P⁵ is opened so that the piston P³ is lowered and the valve P² thus opened so that the pressure fluid within the stack of enclosures N lifts the diaphragms R and moving contacts R¹ thereby causing a blast of deionising fluid to flow first over the separated seatings R, S¹ and thence through the nozzle-like fixed contacts S to the exhaust conduits S². The arcs having thus been extinguished the piston P³ permits pressure gas to flow into the cylinder above the piston P⁷ which moves down and acts through a rotary vertical operating shaft P⁴ and a worm and rack P⁹ within the chamber N¹ on the spindle Q¹ so that the switch Q is opened. The inlet control valve P² is now closed so that the circuit-breaker contacts R¹, S automatically reclose under the action of the biasing springs. The circuit-breaker is now ready for reclosing of the circuit by means of the valve P⁸ controlling the isolating switch Q.

It will be understood that the constructions

above described are given by way of example only and that details may be modified to suit requirements. For example, though the deionising fluid has been described as compressed air, any other suitable gas, or a liquid, may be employed. Moreover, the above examples are described as of the vertical type for convenience of description only, and it will be apparent that the contact enclosure, or stack of enclosures, may be employed in any position other than the vertical.

The invention not only obviates the necessity for providing frictional sliding or guide surfaces for the contacts, which surfaces are vulnerable to the effects of arcing, but ensures that the moving contact of the circuit-breaker cannot be operated to initiate the arc unless and until the fluid pressure necessary to provide the requisite fluid blast at the break is available at the contacts, this advantage being provided whether the enclosure or stack of enclosures is or are maintained under fluid pressure with control by an outlet control valve, or whether the operation of the contacts is by means of an inlet control valve which controls the admission of pressure fluid to the enclosure or enclosures.

What I claim as my invention and desire to secure by Letters Patent is:

1. A fluid-blast electric circuit-breaker comprising a contact enclosure, means whereby fluid under pressure is supplied to the contact enclosure, a rigidly fixed nozzle-like contact within the enclosure and having an exhaust conduit therein, a movable contact within the enclosure and cooperating with the fixed contact said movable contact being operated by the fluid pressure within the enclosure, and a flexible diaphragm within the enclosure locating the movable contact relatively to the fixed contact so that the movable contact bears resiliently against the fixed contact.

2. A fluid-blast electric circuit-breaker as claimed in claim 1, having an auxiliary electrode arranged within the hollow fixed contact.

3. A circuit-breaker unit for a multi-break fluid-blast circuit-breaker having a plurality of circuit-breaker units arranged in an aligned assembly or stack, comprising a contact enclosure means whereby fluid under pressure is supplied to the enclosure, two cooperating contacts arranged within said enclosure, at least one of said contacts being movable, a resilient device supporting said movable contact and constituting the sole guiding means therefor, and means for electrically connecting each of said contacts to the adjacent contact of the next circuit-breaker unit of the aligned assembly or stack.

4. A contact unit for a multi-break fluid-blast circuit-breaker having a plurality of contact units arranged in a series assembly or stack, comprising a contact enclosure means whereby fluid under pressure is supplied to the enclosure, a movable contact operated by the fluid pressure within the enclosure and arranged within and towards one end of the enclosure, a flexible mounting device within the enclosure and constituting the sole guiding means for said movable contact within the enclosure, a fixed contact arranged within and towards the other end of the enclosure, and means electrically interconnecting the said fixed and movable contacts which respectively cooperate with the corresponding movable and fixed contacts of the adjacent units in the stack.

5. A contact unit as claimed in claim 4, in

which the fixed contact is nozzle-like and communicates with an exhaust passage for the fluid-blast which flows between the contacts when they separate.

6. A contact unit as claimed in claim 4, in which the flexible mounting device is of insulating material and the contacts of the unit are electrically interconnected through at least one flexible lead.

7. A multi-break fluid-blast electric circuit-breaker having a plurality of contact units arranged in an aligned assembly or stack to give a plurality of breaks in series, comprising a plurality of contact units arranged end to end and in open mutual communication, each unit including a contact enclosure means whereby fluid under pressure is supplied to the enclosure, a movable contact operated by the fluid pressure within the enclosure and arranged within and towards one end of the enclosure, a flexible mounting device within the enclosure and which constitutes the sole guiding means for said movable contact within the enclosure, a fixed contact arranged within and towards the other end of the enclosure, and means electrically interconnecting the said fixed and movable contacts which respectively cooperate with the corresponding movable and fixed contacts of the adjacent units in the stack.

8. A multi-break fluid-blast electric circuit-breaker having a plurality of contact units arranged in an aligned assembly or stack to give a plurality of breaks in series, comprising a plurality of contact units arranged end to end in open mutual communication, each unit including a contact enclosure, a movable contact arranged within and towards one end of the enclosure, a flexible mounting device within the enclosure and which constitutes the sole guiding means for said movable contact within the enclosure, a fixed contact arranged within and towards the other end of the enclosure, two seating surfaces carried respectively by the two contacts, which seating surfaces respectively cooperate as fluid-tight valve seatings with the corresponding seating surfaces on the contacts of the adjacent units of the stack, and means electrically interconnecting the said fixed and movable contacts which respectively cooperate with the corresponding movable and fixed contacts of the adjacent units in the stack.

9. A multi-break fluid-blast electric circuit-breaker as claimed in claim 8, in which the flexible locating device for the movable contact of each unit is formed of rubber and constitutes one of the valve seating surfaces.

10. A fluid-blast circuit-breaker as claimed in claim 8, in which the flexible mounting device is formed of rubber and constitutes one of the fluid-tight valve seatings.

11. A fluid-blast electric circuit-breaker comprising a contact enclosure, means whereby fluid under pressure is supplied to the said enclosure, a rigidly fixed contact within the enclosure, a movable contact within the enclosure and cooperating therein with the fixed contact, at least one of said contacts having a gas-discharge vent therein, whilst the movable contact is operated solely by the fluid pressure within the enclosure, and a resilient device within the enclosure and supporting the movable contact therein, the movement of the movable contact being guided solely by said resilient device, so that frictional

sliding or guide surfaces for the moving contact, as well as operating mechanism therefor, are obviated.

12. A fluid-blast electric circuit-breaker comprising a contact enclosure, means whereby fluid under pressure is supplied to the enclosure, a rigidly fixed contact within the enclosure, a movable contact within the enclosure and cooperating therein with the fixed contact, at least one of said contacts having a gas-discharge vent therein whilst the moving contact is operated solely by the fluid pressure within the enclosure, and a flexible metal diaphragm within the enclosure and supporting the movable contact therein, the movement of the movable contact being guided solely by said diaphragm, so that frictional sliding or guide surfaces for the moving contact, as well as operating mechanism therefor, are obviated.
13. A fluid-blast electric circuit-breaker comprising a contact enclosure, means whereby fluid under pressure is supplied to the enclosure, a rigidly fixed contact within the enclosure, a movable contact within the enclosure and cooperating therein with the fixed contact, at least one of said contacts having a gas-discharge vent therein whilst the moving contact is operated solely by the fluid pressure within the enclosure, and a flexible rubber diaphragm within the enclosure and supporting the movable contact therein, the movement of the movable contact being guided solely by said diaphragm, so that frictional sliding or guide surfaces for the moving contact, as well as operating mechanism therefor, are obviated.
14. A fluid-blast electric circuit-breaker comprising a contact enclosure, means whereby fluid under pressure is supplied to the enclosure, and a rigidly fixed contact within the enclosure, a movable contact within the enclosure and cooperating therein with the fixed contact, at least one of said contacts having a gas-discharge vent therein, means whereby the movable contact is operated solely by the fluid pressure within the enclosure, a resilient device within the enclosure and supporting the movable contact therein, the movement of the movable contact being guided solely by said resilient device so that frictional sliding or guide surfaces for the moving contact, as well as operating mechanism therefor, are obviated, and seatings carried by the two contacts respectively, the said seatings constituting relatively movable parts of a fluid-tight valve which controls the flow of arc quenching fluid from the enclosure to the said discharge vent.
